TILE PANEL BACKING

Application filed July 2, 1928. Serial No. 289,892.

This invention relates to a backing adapted to hold tile or veneering of like character. Panels having a facing of tile, stone, glass or like material have been found desirable in buildings, store fixtures and elsewhere. Such panels should be light in weight, have veneering firmly affixed to the surface, and not be subject to warping. A wood backing meets these requirements as to weight and ease of installation. However, a single sheet of wood, unless special provisions are made, is subject to warping and expansion, especially in the direction of the fibres. If the difference of the coefficients of expansion of the veneer facing and backing are of substantial magnitude, a strain is exerted on the material binding the facing to the backing, which is often sufficient to cause cleavage between the backing and facing, resulting in chipping, cracking of the facing and breakage. By the use of a yielding cement or adhesive, this has been satisfactorily overcome in many instances. As a further aid in preventing warping, expansion, and cleavage stresses, a neutralizing backing has been used. This has been accomplished by the use of a multiple ply board with the plies arranged with their grains crosswise of one another. Kerfs extending crosswise of the grain have also been employed. These kerfs unless they extend through a ply will not prevent warping. If extended through the ply, warping lateral to the faces may occur. Weakening of the plies also results. The objects of the present invention are to provide a backing of wood having any or all of the following features: slots extending therethrough; expansible binding ties bridging the slots; and ties embedded and keyed in a manner to prevent lateral displacement of the walls of the slots.

These objects together with other objects and corresponding accomplishments are obtained by means of the embodiment of my invention illustrated in the accompanying drawing, in which:

Fig. 1 is a face view of a fragment of a tile panel, part of the facing being broken away to show the backing, and portions of the plies being broken away; Figs. 2 to 5 in-

clusive are sections as seen on the lines correspondingly numbered in Fig. 1.

Referring more particularly to the drawing, a panel comprising a backing A has tiles B secured thereto by an adhesive cement C. The cement is preferably a yielding adhesive having sufficient elasticity to compensate for differences in the coefficients of expansion between the tiles and the backing. Cement D is used to fill the joints, so as to point up the tile facing. The tiles are preferably ceramic and shown crowned and covered on their fronts with a glazed surface. They are impervious to moisture.

The invention resides particularly in the backing, and as shown herein it comprises a three ply board, the plies being indicated by 6, 7 and 8. Each ply is of wood and preferably arranged with its grain crosswise of the grains in the other ply. This provides a neutralized backing which will not warp. Extending through the backing from face to face are a multiplicity of slots 9. These slots provide for distributed expansion, being expansive joints. They also serve for egress of moisture which may become entrapped between the facing and the backing. If such openings are not provided, the moisture must permeate the wood. Such permeation is slow and tends to cause separation of the plies with resultant warping. The slots tend to weaken the backing, and the edges thereof may become displaced. To counteract this, binders 10 are provided. These binders are preferably strips of corrugated metal, which are disposed to bridge the slots and are embedded in the sheet. They tie the edge walls of the sheets and the slots together. In order to provide for holding the sheets against lateral displacement at the slots, the binders are preferably upset as indicated by 11 in Fig. 4. This keys the binders and securely locks the sheet at the slots. It is obvious that I have provided a backing, which is non-warpable, permits quick hardening of the adhesive, and has sufficient flexibility to adapt itself to the tiles.

What I claim is:

1. A backing for the purpose described comprising a sheet of fibrous material with

a multiplicity of elongated slots extending therethrough from face to face, and corrugated binder strips bridging said slots and embedded at their ends in said sheet, the edges of said strips being keyed at their ends to said sheet to prevent lateral displacement of the walls of said sheet at the slots.

5 2. A backing for the purpose described comprising a multiple ply wood sheet, said 10 plies being disposed with their grains crosswise, a multiplicity of elongated slots extending through said sheets from face to face, and corrugated binder strips bridging said slots and embedded at the ends in said sheet, said strips being co-extensive with the thickness of said sheet.

15 3. A backing for the purpose described comprising a sheet of non-warpable material with a multiplicity of elongated slots extending 20 therethrough from face to face, and corrugated binder strips bridging said slots and embedded at their ends in said sheet, said strips being coextensive with the thickness of said sheet; the edges of said strips being 25 keyed at their ends to said sheet to prevent lateral displacement of the walls of said sheet at the slots.

30 4. A backing for the purpose described comprising a sheet of non-warpable material with a multiplicity of elongated slots extending 35 therethrough from face to face, and corrugated metal binder strips bridging said slots and embedded at their ends in said sheet, said strips being co-extensive with the thickness of said sheet; the edges of said strips being upset to key the strips to said sheets 40 and prevent lateral displacement of the walls of said sheet at the slots.

45 5. A backing for the purpose described comprising a multiple ply wood sheet, the plies being disposed with their grain extending crosswise, a multiplicity of elongated slots extending through said sheet from face to face, and corrugated metal binder 50 strips bridging said slots and embedded at their ends in said sheet, said strips being co-extensive with the thickness of said sheet, the edges of said strips being upset at their ends to key said sheet and prevent lateral displacement of the walls of said sheet at the slots.

In witness that I claim the foregoing I have hereunto subscribed my name this 7th day of June, 1928.
